SHOE HOLDER

Stanley E. Raudebaugh, East Cleveland, Ohio

Application September 6, 1946, Serial No. 695,269

11 Claims. (Cl. 12—125)

1

This invention relates to a shoe holder and more particularly a holder which is adapted to firmly secure a shoe on a support to facilitate the cleaning and polishing thereof with a minimum of effort. Shoe holders for shining shoes are usually provided with a shoe holding form inserted into the inside of the shoe detachably connected to a support or wall or the bracket of a chair. Sometimes a foot rest is provided in addition to the shoe holding form which has also been detachably secured to the chair or other support as a bracket.

Desirable features for a shoe holder are simplicity, lightness, strength and ease of application of the shoes to be polished, and these features are generally obtained within practical limitations on shoe holders now in conventional use. However, shoe holders heretofore shown have been deficient in simplicity of design combined with rigidity of mounting and in securely holding the shoe while it was being polished and thereby failed to provide a support for the shoe equal to that afforded by the human form, namely, the foot of the wearer resting on the foot rest of the shoe shiner's chair or stand.

It is known that to properly restore a worn shoe to its original shape and polish, it is necessary to stretch the upper shoe leather to remove wrinkles which form on top of the shoe after it has been worn for a time by the wearer, and this stretching of the upper leather portion of the shoe is accomplished by pressing the toe portion of the shoe as well as the foot of the wearer, down upon and over the foot rest of the shoe shiner's chair or stand by means of a polishing cloth in the hands of the shoe shiner. To effect this result the foot rest on the shoe shiner's chair or stand is made shorter than the shoe so that the latter extends to a certain extent over the foot rest. The shoe as well as the foot of the wearer being flexible responds readily to the pressing action of the polishing cloth in the hands of the shoe shiner. Also when brushing the shoes a similar action takes place although to a lesser degree. A shoe holder of the invention will permit this stretching action in the upper surface of the shoe to take place during the polishing operation, and consequently will facilitate the removal of the wrinkles in the shoe leather and thereby will enable the shoe shiner to restore the shoe to its original shape with a satisfactory polish.

It is therefore an object of the invention to provide a shoe holder that will permit downward flexing of the toe portion of the shoe rela-

2

tive to the rear portion during polishing of the shoe so that the shoe can be restored to its original shape free of any wrinkles in the upper surface of the shoe with a satisfactory polish.

5 Another object of the invention is to employ means for rigidly holding the rear or heel portion of the shoe while the toe portion is being flexed and to prevent any substantial sideways movement of the toe portion of the shoe during the 10 polishing operation.

Another object of the invention is to provide 15 rigid means for supporting the bottom of the sole of the shoe intermediate the heel and toe portions so that the toe portion can be flexed relative to the rear or heel portion to thereby permit the stretching of the shoe upper in the polishing operation.

A still further object of the invention is to provide 20 a shoe holder which is simple and which contains a minimum number of parts while at the same time affording the aforementioned benefits.

Other objects and a fuller understanding of 25 the invention may be had by referring to the following description and claims, taken in conjunction with the accompanying drawings in which like parts are designated by like reference characters and in which:

30 Figure 1 is a top plan view of a shoe holder embodying the invention.

Figure 2 is a view in side elevation of the shoe 35 holder shown in Figure 1.

Figure 3 is an end view of the shoe holder shown in Figure 2.

Figure 4 is a cross-sectional view taken on line 40 4—4 of Figure 1.

Figure 5 is a top plan view of a modification 45 of a part of the shoe holder embodying the invention.

Figure 6 is a view in side elevation of the shoe 50 holder shown in Figure 5.

Referring to the drawings, it will be seen that the embodiment of the invention, as shown, comprises 55 a plate member 11 which may be secured as at 12, on a door frame or other convenient support. The plate 11 may be rectangular in shape as shown in Figure 3 and may be provided on one side with a slot 13 trapezoidal in shape having a bottom 14 and side walls 15 and 16 converging inwardly at an angle toward the longitudinal center of the slot. The plate 11 may be mounted with the shorter base 17 of the slot downward so as to wedgingly support a shoe holder bracket to be described below.

The shoe holder further consists of a bracket member 18 formed of suitable material, such as metal, having a vertical portion or column 19, an integrally attached substantially horizontal supporting base plate 20 and an integrally attached outwardly extending upper portion 21 which may be shorter than the base plate member 20. In order to give strength and rigidity to the bracket member the vertical portion 19 may be constructed in the shape of a channel having a base 22 and side flanges 23. Integral with the base portion 22 of the column 19, there are provided, intermediate its ends, downwardly tapered flanges 24 which together with the base portion 22 form a trapezoidal plate with its edges shaped to conform to the shape of the slot 13 in the plate member 11, and thereby being adapted to be slipped downwardly in the slot 13 in a manner to detachably mount the bracket member on the plate member 11. Other conventional mounting means may be used if desired or the bracket 18 may be screwed or bolted directly to the wall, door frame or post, either permanently, or so as to be detachable when not in use. For such direct mounting holes 25 may be provided in the base portion 22 of the vertical bracket portion 19 as well as in the flanges 24 thereof for fastening elements such as screws or bolts not shown.

On the upper surface of the base plate member 20 may be provided, adjacent the vertical column 19, a pad 26 having an arcuate shaped front wall or surface portion 27 adapted to fit the contour of the back of the heel of a shoe mounted on the plate member 20. The outer end of the plate member 20 remote from the vertical column 19 is disposed upwardly as at 28 to a point not substantially higher than the thickness of the heel of the shoe to be placed on the holder for cleaning and polishing. The base plate member 20 is preferably extended outwardly from the vertical column 19 of the bracket so that the outer end portion 28 reaches a point intermediate the toe and inside surface of the heel of the shoe to be placed in the holder. In order to give strength and rigidity the plate member 20 may be provided with bottom ribs 29 and upper ribs 30.

The integrally attached upper member 21 may also be extended substantially horizontal from the vertical column 18 although a satisfactory bracket construction will result if this upper member is inclined either upwardly or downwardly from a horizontal plane or alternately constructed so as to terminate in a lug sufficient to form a bearing point or stop for a cam to be described. This upper member may be formed by extensions 31 and 32 of the side flanges 23 of the vertical column 19, the base portion 22 terminating at 33 to afford an open space 34 between the extensions 31 and 32 for a purpose to be described below.

At the outer ends of the extensions 31 and 32 are provided bearing holes 35 in which an arbor or pin 36 is rotatably mounted. The arbor 36 may be provided with riveted ends or heads 37. On the arbor 36 is rigidly mounted a cam plate 38 having flat walls 39, an arcuate cam surface 40 and a handle 41. The cam plate has a thickness slightly less than the space between the extensions 31 and 32 of the upper member 21 so that the cam plate 38 will be adapted to move freely between these extensions in a manner and for a purpose to be described. The cam plate is mounted on the arbor 36 so that the

arcuate cam surface 40 will be eccentric to the arbor or pivot point of the cam plate. Below the cam plate 38 is positioned a shoe heel last or filler block 42 having a flat bottom or base portion 43 of a shape to generally conform to the inside bottom heel portion of a shoe to be mounted on the shoe holder, and may be further provided with sides 44 and 45 and a rounded end portion 46 to conform to the inside contour of the back of the shoe. The filler block is also made long enough above the base portion so as to preferably extend above the top of the back portion of the shoe although that may not be necessary for all shoes for which the holder may be adaptable. In the top surface of the filler block is provided a slot 47 extending from the rounded end portion 46 to the opposite end thereof. This slot is formed with sides 48 and 49 spaced apart a distance only slightly greater than the width of the cam plate 38 so that when the filler block is positioned below the cam plate the cam plate will have a snug sliding fit in the slot when the parts are assembled in securing a shoe on the shoe holder in the manner to be described. The slot 47 is further provided with a bottom portion 50 tapered slightly from the rounded end portion 46 to the opposite side thereof so that the vertical distance from the bottom portion 50 of the slot to the bottom surface 43 of the filler block at the rounded end is less than the distance from the bottom of the slot at the side of the filler block opposite the rounded end portion thereof to the bottom surface 43. This taper in the bottom surface 50 of the slot may preferably be about $\frac{1}{4}$ " per foot although blocks having no taper or tapers varying up to $\frac{1}{2}$ " per foot may be used with satisfactory results. The slot 47 is also made deep enough so that when the filler block 42 is so positioned below the cam plate 38 in the operation of the shoe holder with the arcuate surface portion of the cam plate pressed against the bottom surface 50 of the slot the side walls 39 of the cam plate will hold the filler block 42 rigid so that it cannot turn. Due to variations in the size and styles of shoes adapted to be cleaned and polished on the shoe holder of the invention a number of different sizes and shapes of filler blocks may be used with the holder, all however having the common characteristic of the base 43 and slot 47 as described and shown in Figures 1, 2 and 3 of the drawings.

In the operation of mounting a shoe on the shoe holder, the bracket member 18 is first inserted in the plate member 11, the latter having previously been secured to a wall or post. The last or filler block 42 is then inserted inside the heel portion of a shoe to be cleaned and polished with the slot 47 positioned uppermost and substantially parallel to the longitudinal axis of the shoe. After the filler block has been pushed well into the inside rear portion of the shoe, the latter with the filler block extending upward therefrom is placed on the plate member 20 of the bracket with the back part of the heel of the shoe abutting the arcuate shaped front wall 27 of the pad 26. The cam plate 38 is then turned on its axis so that the lower edge thereof is positioned in the slot 47 in the filler block 42. With the cam plate 38 held in this position and the shoe with the filler block therein mounted on the base plate 20, the cam plate is rotated by means of the handle 41 so as to press the cam against the bottom of the slot 47 in the filler block. That action when completed wedges the

eccentric cam plate 38 tightly into the slot 47 of the filler block 42 and the shoe becomes tightly clamped onto the base plate 20 of the shoe holder ready to be cleaned and polished.

The holes 35 for the arbor 36 of the cam plate 38 are positioned in the upper portion 21 of the bracket 18 relative to the vertical column 19 of the bracket, the base plate portion 20, the outer end portion 28 of the latter, and the arcuate shaped front surface 27 of the pad 26 of the bracket, so that when a shoe is mounted on the bracket and the cam plate 38 and the filler block 42 are in assembled relationship the sole of the shoe mounted on the bracket of the holder forms the base of a right angled triangle whose vertical leg passes through the heel of the shoe, the filler block 42, and the axis of rotation of the eccentric cam plate 38. The action of the shoe shiner's polishing cloth on the front or toe portion of the shoe in the polishing operation tends to bend that portion of the shoe downward over the outer end portion 28 of the base plate member 20 which is desirable in order to remove any creases or wrinkles from the upper surface of the shoe. The base plate member 20 being strong and rigid will not give and be pressed downward but will cooperate with the heel portion of the shoe and the other portions of the shoe holder bracket, the filler block and eccentric cam plate to maintain the aforesaid triangle of forces to hold the shoe securely in the holder during the polishing operation.

In the modified form of a part of the shoe-holder of the invention shown in Figures 5 and 6, a filler block 42' is connected to the toe-former 51 of a conventional type of shoe-tree. In this adaptation the toe-former 51 may be constructed in two sections 52 and 53 of a shape to conform generally to the contour of the forepart of the human foot. These toe-former sections may be pivotally attached, as at 54, to telescoping shank members 55 and 56, the latter being rigidly attached to the filler block or heel-former section 42'. These two shank members may also have toggle links 57 and 58 pivotally attached thereto and to each other in such a manner that the shoe-tree will be readily adaptable to shoes of different shapes and sizes and may be readily and quickly manipulated to expand or contract the tree in the shoe and in correlation with the respective parts of the shoe holder securely mount the shoe in the holder for cleaning and polishing. No further details of the adaptation of the invention to a shoe-tree for mounting a shoe on the holder are thought to be necessary as recourse may be had for further details to any conventional form of shoe-tree of the general type shown such for example as disclosed in the Anderson Patent 1,116,666, the construction of the shoe-tree other than the adaptation of it to the heel-former or filler block 42 of the invention forming in itself no part of the invention.

It is believed that the many advantages of a shoe holder constructed in accordance with the present invention will be readily understood and although a preferred embodiment of the device is as illustrated and described, it is understood that the specific embodiment shown and described has been given by way of illustration and not by way of limitation and that the structure above described is subject to a wide variation and modification without departing from the scope or intent of the invention all of which variations and modifications are to be included within the scope of the present invention.

What is claimed is:

1. A shoe holder consisting of a bracket, a cam pivotally attached to the bracket and a shoe heel-last having a groove adapted to be wedgingly associated with the said cam to detachably secure a shoe on the bracket.
2. A shoe holder consisting of a support, a bracket detachably mounted on the support, a cam pivotally attached to the said bracket and a shoe heel-last having a groove adapted to be wedgingly associated with the said cam to detachably secure a shoe on the bracket.
3. A shoe holder consisting of a bracket having a vertical member, an integral outwardly extending upper member and an integral substantially horizontally extending lower member longer than the said upper member adapted to support the heel and sole of a shoe, means engageable in the inside rear portion of a shoe mounted on the said bracket, and a cam pivotally mounted on the said bracket and engageable with the said means for releasably securing the heel of the shoe between the said means and the said bracket.
4. A shoe holder consisting of a bracket having a vertical member, and an integral member extending from the lower end of the said vertical member outwardly and upwardly, an edged cam pivotally attached to the upper end of the said vertical member and a shoe heel-last having a groove adapted to be wedgingly associated with an edge of the said cam to detachably secure a shoe on the said integral lower member.
5. A shoe holder consisting of a bracket having a vertical member and an integral member extending from the lower end of the said vertical member outwardly and upwardly, a cam pivotally attached to the upper end of the said vertical member, the pivot point of the said cam being positioned in a straight line passing substantially perpendicularly through the said integral lower member, and a shoe heel-last and the heel of a shoe mounted on the said integral lower member.
6. A shoe holder consisting of a bracket having a vertically disposed body member and an integral member extending from the lower end of the said body member outwardly and upwardly, an edged cam pivotally attached to the upper end of the said body member, a shoe-tree having a heel-last and a toe-last adjustably attached to the heel-last, said heel-last having a groove in one surface thereof adapted to be wedgingly associated with an edge of the said cam to detachably secure a shoe on the holder.
7. A shoe holder consisting of a bracket having a vertically disposed body member, an integral outwardly extending lug on the upper end of the said body member and an integral outwardly extending arm on its lower end, the outer end of the said lower member extending upwardly, an edged cam pivotally attached to the said lug, a shoe-tree having a heel-last and a toe-last adjustingly attached to the heel-last, said heel-last having a groove adapted to be wedgingly associated with an edge of the said cam to detachably secure a shoe on the holder.
8. A bracket for a shoe holder consisting of a vertically disposed body member, an integral outwardly extending upper member and an integral member extending outwardly and upwardly at its lower end, said upper member having a bearing.
9. A bracket for a shoe holder consisting of a vertically disposed body member having a bearing at its upper end and a substantially straight integral member extending from its lower end

outwardly and upwardly, said bearing being positioned in a straight line passing substantially perpendicularly through the said integral lower member.

10. A bracket for a shoe holder consisting of a vertically disposed body member having a bearing at its upper end, a shoulder at its lower end and a substantially straight integral member extending outwardly from the said body member below the said shoulder, said bearing being positioned in a straight line passing substantially

perpendicularly through the said integral lower member.

11. A filler block for a shoe holder having a bracket and an edged cam mounted on the bracket, the said filler block having a bottom portion adapted to fit in the inside heel portion of a shoe mounted on the bracket, a vertical body portion and a top surface having a bottomed slot adapted to receive an edge of the said cam.
